UNITED STATES PATENT OFFICE.

RICHARD STANLEY DOWELL AND ALBERT WALTON DOWELL, OF LONDON, ENGLAND.

INFANT'S FEEDING BOTTLE AND THE LIKE.

Application filed June 26, 1924. Serial No. 722,597.

This invention relates to infants' feeding bottles and like receptacles of the kind having a stopper positioned opposite the usual nipple end adapted to act as a valve for the purpose of permitting the admission of the air into the receptacle as the contents are withdrawn through the nipple or of cutting off communication between the interior of the vessel and the air when required.

The object of the present invention is to provide an improved form of feeding bottle or the like of the above character, and the invention consists in an infant's feeding bottle or the like of the kind referred to having a slot or groove in the neck of the bottle or the like (or in the stopper) and a recess in the stopper (or in the neck of the bottle or the like) adapted to register with the slot or groove and connected with the inner end of the stopper (or adjacent part of the neck) by a sinuous, wavy, curved, zig-zag or like groove or channel, the arrangement being such that there is thus imposed an obstacle or restriction in the way of the passage of the contents of the receptacle while free ingress of air thereinto is permitted.

The invention also consists in the form of apparatus hereinafter described or indicated.

The accompanying drawings illustrate one mode of carrying out the invention.

Figure 1 is a plan of one convenient form of infant's feeding bottle in accordance with the invention with the parts in position for the admission of air.

Figure 2 is a similar view but with the admission of air shut off.

Figure 3 is a plan of the stopper shown in Figures 1 and 2 and

Figure 4 is an end view showing the neck of the bottle.

In carrying our invention into effect in the manner illustrated we provide in the interior of the neck *a* of the bottle a slot or

like opening *b* which extends into the neck 45 for a portion only of the length of the stopper inserted therein. The stopper *c* is formed or provided with a recess *d* therein and such recess is connected with the inner end of the stopper by means of a curved, 50 zig-zag or other broken or indirect duct or channel *e*. The arrangement is such that when the stopper is turned into the position shown in Figure 1 in which the recess *d* registers with the slot *b* in the bottle-neck 55 air is freely admitted to the interior of the receptacle while owing to the formation of the air passage the contents of the receptacle are prevented from escaping through the air duct. When, however, the stopper is turned 60 so that the recess *d* is out of register with the slot *b* as shown, for example, in Figure 2 the communication between the air and the interior of the receptacle is completely broken.

It will of course be understood that the stopper may be furnished with a slot and the sinuous, zig-zag or other similar duct may be formed in the bottle-neck and the invention is not to be limited to any particular kind or construction of receptacle to 70 which the invention is to be applied.

Having now described our invention, what we claim as new and desire to secure by Letters Patent is:—

An infant's feeding bottle or the like of 75 the kind referred to comprising a neck portion and a stopper adapted to fit therein, one of said parts having a recess communicating with the atmosphere and adapted to register with a recess in the other of said parts, said 80 last mentioned recess being connected with the interior of the receptacle by a sinuous channel arranged laterally of said recess.

In testimony whereof we have signed our names to this specification.

RICHARD STANLEY DOWELL.
ALBERT WALTON DOWELL.
